(57) **CLAIM**

The ornamental design for a induction trash can as shown and described.

DESCRIPTION

FIG. 1 is a perspective view showing my new design.

FIG. 2 is a front view thereof.

FIG. 3 is a rear view thereof.

FIG. 4 is a left end view thereof.

FIG. 5 is a right end view thereof.

FIG. 6 is a top view thereof; and,

FIG. 7 is a bottom view thereof.

The portions shown encircled by broken lines and deemphasized in FIG. 7 illustrate portions of the induction trash can that form no part of the claimed design.
